CLAIM

The ornamental design for a pedestal based arm chair, as shown and described.

DESCRIPTION

FIG. 1 is a front perspective view of a pedestal based arm chair embodying our new design;

FIG. 2 is a front elevational view of the design;

FIG. 3 is a top plan view of the design;

FIG. 4 is a rear elevation view of the design;

FIG. 5 is a side elevational view of the design, the opposite side being substantially a mirror image thereof;

FIG. 6 is a front perspective view of a pedestal based arm chair showing a second embodiment of our design;

FIG. 7 is a front elevational view of the second embodiment of the design;

FIG. 8 is a top plan view of the second embodiment of the design;

FIG. 9 is a rear elevation view of the second embodiment of the design;

FIG. 10 is a side elevational view of the second embodiment of the design, the opposite side being substantially a mirror image thereof;

FIG. 11 is a front perspective view of a pedestal based arm chair showing a third embodiment of our design;

FIG. 12 is a front elevational view of the third embodiment of the design;

FIG. 13 is a top plan view of the third embodiment of the design;

FIG. 14 is a rear elevational view of the third embodiment of the design; and,

FIG. 15 is a side elevational view of the third embodiment of the design, the opposite side being substantially a mirror image thereof.

The broken line showing on the seat and backrest represents a seam line.

The broken line showings of a pedestal base and an adjustment mechanism are for environmental purposes only and form no part of the claimed design.
